UNITED STATES PATENT OFFICE.

MESHACK DAVIS, OF SCHLATER, MISSISSIPPI.

FOLDING FEED BOX.

1,422,422.

Specification of Letters Patent. Patented July 11, 1922.

Application filed August 13, 1921. Serial No. 491,963.

To all whom it may concern:

Be it known that I, MESHACK DAVIS, a citizen of the United States, residing at Schlater, in the county of Leflore and State of Mississippi, have invented certain new and useful Improvements in Folding Feed Boxes, of which the following is a specification, reference being had to the accompanying drawings.

10 This invention relates to feed boxes, and particularly to a portable feed box.

An object of the invention is to provide a device of this character wherein the sides and ends of the box are foldable to render 15 the box compact and portable.

It is also an object of the invention to provide a feed box of this character wherein one of the side members is provided with a flexible or resilient bail which not only provides means for carrying the box from place 20 to place, but which is also capable of being used to support the feed box by engagement with a suitable object.

It is still a further object of the invention 25 to provide a device of this character wherein the means used to hold the various parts in their folded position is also used to hold said parts in their extended position in engagement with each other.

30 With these and other objects in view, the invention consists in the improved construction and arrangement of parts to be hereininafter more particularly described, fully claimed, and illustrated in the accompanying 35 drawings, in which:—

Figure 1 is a side elevation of a folding feed box constructed in accordance with an embodiment of the invention, and showing the box in its folded position.

40 Figure 2 is an end elevation showing one of the end members extended, and the sides and opposite end members of the box in their folded positions.

Figure 3 is a perspective view of the device in its extended position, showing the means for securing the box to a support.

Referring to the drawings, 5 designates a base or bottom which may be made in various sizes, said bottom having a pair of 50 transversely extending spaced cleats 6, which depend from the lower surface of said base or bottom, an eye 7 being carried by the ends of the cleats, the purpose of which will be hereinafter described. Secured to the 55 upper surface of the base or bottom, at the

end of the bottom, and extending transversely thereof, is a pair of cleats 8. Hinged as at 9 to each of the cleats 8 is an end member 10, each end member having an extension 11 which projects from the inner face of 60 said end member and adjacent the ends of the member. Each of the extensions 11 is provided with fastening means such as hooks 12 which at times are adapted to engage the eye 7. It will be noted that the 65 ends of each of the side members extend beyond the side portion of the base or bottom, so as to permit the extensions 11 to be disposed parallel to the side edges of the bottom.

Hinged to the longitudinal or side edges of the upper surface of the bottom 5 are side members 13, said side members being adapted to swing inwardly of the bottom and to engage said bottom in their folded 70 position. It will be noted that the cleats 8 correspond in height to the thickness of the sides, so that when the sides are folded they are disposed flush with the upper surface of the cleats to permit the end portions to 75 be readily folded upon the side members. In addition to providing supports for the hooks 12, the extensions 11 are also used to properly position the side members with respect to the end members by engaging the outer 80 faces of the side members, the outer faces of the side members adjacent their end portions being provided with eyes 14 adapted to receive the hooks 12. It will be noted that the outer edge of each extension is cut away 85 so as to prevent interference with the hooks 12 when engaging the eyes 14. The end members 10 are also provided with recesses 90 adapted to receive the eyes 14 when the sides and ends are in their folded positions. When the side members 13 are disposed in their folded position, that is engaged with the bottom member or base 5, they are locked by means of a latch 15, the keeper 16 of the latch being carried by the outer face of one 95 side member, while the latch proper is carried by the outer face of the opposite side member.

The end members are adapted to be swung inwardly upon the side members and are 100 guided in this movement by means of the extensions 11 which are disposed closely adjacent the longitudinal edges of the base. This movement brings the hooks 12 substantially in alignment with the eyes 7 so that 110

said hooks may be engaged with the eyes to lock the sides and ends to the base, and prevent accidental movement thereof.

To extend the box for use, the hooks 12 are unfastened and the ends 10 swung outwardly into engagement with the cleats 8. The latch 15 is then operated to release the side members which are then swung upwardly and into engagement with the inner faces of the extensions 11. The hooks 12 are inserted in the eyes 14 and the device is then ready to receive the feed.

It is of course obvious that it is not always convenient to support a feed box. With applicant's device, this disadvantage is overcome by the provision of novel holding means having a double function. This means comprises a coil spring 17 which may be made relatively long, said spring having eyes 18 and 19 provided at its ends. The eye 18 of the spring is adapted to engage an eye member 20 carried by the outer face of one of the side members, while the eye 19 is adapted to detachably engage a hook member 21 carried by the same side member in spaced relation to the eye 20, and inwardly of the path of movement of the end members when said side and end members are being folded. After the device has been extended for use, the base 5 may be placed upon the hub of a wheel or like projection and the spring 17 extended around one of the spokes or an adjacent object. The eye 19 is then engaged with the hook to properly clamp the feed box and prevent the same from being accidentally disengaged. It may be likewise supported upon a post, as the resiliency of the spring will prevent the box from becoming accidentally disengaged from the post. After the sides and ends have been folded, and the spring disengaged from the

supporting object, the eye 19 may be engaged with the hook member 21 to provide a bail or handle by means of which the feed box may be conveyed from place to place. 45

From the foregoing it will be readily seen that this invention provides a novel folding feed box which may not only be rendered compact in order to permit the box to be conveniently handled but which is provided 50 with novel means for efficiently supporting the box when in use.

What is claimed is:—

1. A device of the character described comprising a receptacle, a yieldable bail 55 connected at one end to one of the foldable members of the receptacle, and adapted to extend around a suitable support, and means carried by said member of the receptacle for the reception of the opposite end of the bail 60 to hold said bail in binding engagement with the support.

2. A device of the character described comprising a base member, cleats carried by the lower surface of said base member, eyes 65 projecting from the ends of the cleats, cleats carried by the upper surface of the base member, end members hinged to said cleats and projecting beyond the ends of said cleats and sides of the base member, extensions carried by the inner surface of said end members, side members hinged to said bottom member and arranged for movement inwardly of the extensions and into engagement with the extensions, eyes carried by 75 said side members adjacent the extensions, and fastening means carried by said extensions for alternate engagement with the eyes of the side members and eyes of the cleats.

In testimony whereof I hereunto affix my 80 signature.

MESHACK DAVIS.
